UNITED STATES PATENT OFFICE.

CLIFFORD W. EGERTON AND JEFFERSON W. HANF, OF BROOKLYN, NEW YORK.

HOSE-SUPPORTER.

1,376,750.

Specification of Letters Patent.

Patented May 3, 1921.

Application filed April 7, 1920. Serial No. 371,810.

To all whom it may concern:

Be it known that we, CLIFFORD W. EGERTON and JEFFERSON W. HANF, citizens of the United States, residing at New York city, 5 borough of Brooklyn, county of Kings, and State of New York, have invented a certain new and useful Hose-Supporter, of which the following is a specification.

This invention is a hose supporter adapted to be worn by the male sex, for the purpose of precluding the sagging of socks, and the object of the invention is to provide a hose supporter, which may support the sock without necessitating attachment thereto.

Men's hose supporters, as heretofore constructed, usually embody a loop adapted to be secured about the leg above the calf, and to which is attached one or more fasteners adapted to grip or be secured to the sock near the upper edge thereof. Such garters manifestly support the sock from the points of attachment therewith, and as these points of attachment are usually at the front portion of the sock, unsightly and uncomfortable sagging of the sock at the back usually results. Moreover, in garters of the type referred to which have one or more points of attachment to the sock, the loop which encircles the leg above the calf must necessarily grip the leg tightly in order to preclude slipping down of the garter, and, moreover, such garters invariably embody metal parts, which become corroded or discolored and frequently impress themselves 35 into the limb of the wearer.

The object of the present invention is to provide a garter, which is not secured in any wise to the sock, but embraces the sock at all points around the limb and supports 40 the sock against sagging entirely through frictional engagement therewith.

A further object of the invention is to provide a one-piece garter for socks, so constructed that it will engage with the sock 45 below the calf and encircle the limb above the calf.

Another object of this invention is to provide in a one piece garter, a structure which is entirely self adjusting and which 50 embodies no relatively movable parts nor metallic elements, but is simple in construction, economical to manufacture, and efficient and durable in use.

Features of the invention, other than those 55 specified, will be apparent from the herein-after detailed description and claims, when

read in conjunction with the accompanying drawings.

The accompanying drawings illustrate one practical embodiment of the invention, 60 but the construction therein shown is to be understood as illustrative, only, and not as defining the limits of the invention.

Figure 1 is a front elevation of a limb on which the garter of the present invention is 65 in place.

Fig. 2 is a side elevation of the showing of Fig. 1.

Fig. 3 is a view of the garter detached from the limb. 70

Fig. 4 is a section on the line 4—4 of Fig. 3; and,

Fig. 5 is a section on the line 5—5 of Fig. 4.

In constructing a garter in accordance 75 with the present invention, a suitable length of elastic tape A is manipulated into the Fig. 8 shape shown in Fig. 3 of the drawings, in such manner that the free ends a of the tape are brought together at a point 80 where the two tapes cross and the crossing tapes may be united at this point to simultaneously sew the ends of the tape together and the crossing sections to one another.

In a highly efficient method of manufacturing the garter, a label B provided with a suitable trade mark or other advertising matter is wrapped around the free ends of the tape, so as to inclose said ends as shown in Fig. 5, and thereafter the parts are 90 stitched together as shown in Fig. 3. In this mode of manufacture, the stitching of the label in place serves to simultaneously secure the free ends a of the tape together and simultaneously attach those portions of the 95 tape which overlie one another at the point of crossing. A garter made in this manner may be very cheaply constructed and is, moreover, reinforced by the label. Usually the attaching of labels to articles is a separate and independent operation carried on at more or less expense, but in the preferred manner of making the garter of this invention, the act of attaching the label results in the formation of the garter. 100

When a garter is constructed as shown in Fig. 3, the resulting 8-shape comprises two separate and distinct loops C and D, which are so proportioned during the making of the garter, that when applied to the limb of 110 the wearer as shown in Figs. 1 and 2, the loop C will embrace the limb above the calf,

while the loop D will embrace the hose below the calf. The advantages resulting from this arrangement are numerous, but probably the most important is that the sock 5 is held all the way around without any positive attachment to the sock. The garter frictionally grips the sock in such manner as to impose no strain whatsoever thereon, yet to preclude slipping or sagging of the 10 sock. With garters embodying the present invention, the sock will not become torn or rust will not be produced as is so frequently the case with garters which are positively secured to one or more parts of the sock by 15 clips or the like.

The garter of this invention is entirely devoid of metal parts and is practically a one-piece construction. It requires no adjustments as it automatically adjusts itself to 20 the contour or size of the limb and readily flexes or gives when the wearer is walking so as not to bind the muscles of the calf and cause discomfort.

The present invention has been particularly described as adapted for use by men, but, as certain ladies are in the habit of 25 wearing socks during the summer, it is to be understood, that the invention is applicable to use by either sex.

Having thus fully described the invention, what I claim as new and desire to secure by Letters Patent is:

1. A garter embodying an elastic tape, the free ends of which are united to an intermediate portion of the tape to form the tape 35

into an 8-shaped configuration, providing a pair of permanent elastic loops, one of which is adapted to embrace the limb above the calf and the other of which is adapted to embrace the sock below the calf.

2. A garter embodying an elastic tape, the free ends of which are firmly and permanently sewed to an intermediate portion of the tape to form the tape into an 8-shaped configuration, providing a pair of permanent elastic loops, one of which is adapted to embrace the limb above the calf and the other of which is adapted to embrace the 40 45 sock below the calf.

3. A garter embodying an elastic tape 50 formed into an 8-shaped configuration with the free ends of the tape overlying the intermediate portion of said tape, a binding member wrapped about those portions of the tape adjacent the free ends thereof, and 55 stitches securing the binding member to the tape and the crossing portions of the tape to one another.

4. A garter embodying an elastic tape formed into an 8-shaped configuration with 60 the free ends of the tape overlying the intermediate portion of said tape, a label wrapped about those portions of the tape adjacent the free ends thereof, and stitches securing the label to the tape and the crossing 65 portions of the tape to one another.

In testimony whereof, we have signed our names to this specification.

CLIFFORD W. EGERTON.
JEFFERSON W. HANF.
